Primary Examiner — Ian Simmons*Assistant Examiner* — Shannon Morgan(74) *Attorney, Agent, or Firm* — McDermott Will & Emery LLP(57) **CLAIM**

The ornamental design for a drink container, as shown and described.

DESCRIPTION

FIG. 1 is a top, front, right perspective view of a drink container showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; the right side being an identical mirror image thereof; and,

FIG. 7 is a cross-sectional view thereof taken along line 7-7 of FIG. 2.

The broken lines in FIG. 7 of the drink container are for the purpose of illustrating environment, and form no part of the claimed design.
